UNITED STATES PATENT OFFICE.

HUBERT R. HUMPHREY, OF KALAMAZOO, MICHIGAN, ASSIGNOR TO GENERAL GAS LIGHT COMPANY, OF KALAMAZOO, MICHIGAN.

GAS STOVE.

Application filed November 6, 1925. Serial No. 67,277.

My improved gas stove is especially designed by me as a cooking stove although certain features thereof are desirable for embodiment in heating stoves.

5 The main objects of the invention are:

First, to provide an improved gas stove which is highly efficient for broiling, roasting and like purposes and which is highly efficient and requires a minimum of attention 10 on the part of the operator.

Second, to provide an improved stove having these advantages which is readily adapted for a variety of uses.

Third, to provide an improved gas stove 15 of the radiating element type which is well adapted for structures of considerable size and at the same time is strong and rigid.

Objects pertaining to details and economies of my invention will definitely appear 20 from the detailed description to follow. The invention is clearly defined and pointed out in the claims.

A structure embodying the features of my invention is clearly illustrated in the accompanying drawing forming a part of this application, in which:

Fig. 1 is a front perspective view of a structure embodying the features of my improvements.

30 Fig. 1^A is a front perspective view of the skeleton or main supporting portions of the frame.

Fig. 2 is a vertical section on a line corresponding to line 2—2 of Fig. 1.

35 Fig. 3 is a fragmentary view partially in section on a line corresponding to line 3—3 of Fig. 1 showing details of the driving means.

Fig. 4 is a fragmentary front elevation 40 with the hearth plate removed.

Fig. 5 is a fragmentary section on a line corresponding to line 5—5 of Fig. 2.

Fig. 6 is a fragmentary perspective view 45 illustrating a grill in operative position.

Fig. 7 is a detail section on a line corresponding to line 7—7 of Fig. 3 showing details of the supports for the spit and grill.

50 Fig. 8 is a detail section on a line corresponding to line 8—8 of Fig. 6 showing details of the stop for limiting the movement of the supporting bars when the grill is in use.

Fig. 9 is a detail view partially in section 55 on a line corresponding to line 9—9 of Fig. 7 showing details of the driving means.

Fig. 10 is a section on a line corresponding to line 10—10 of Fig. 9 showing further details of the driving means.

Referring to the drawing, the supporting parts or skeleton of the body or casing of 60 my improved heater comprise a pair of end members 1 which are preferably a casting and have extended base portions 2 terminating in feet 3 and forwardly projecting overhanging top portions 4.

65 The end members are provided with attaching lugs 7 adapted to receive the bolts 8 securing the back frame 6 thereto. The back frame has a panel 9 secured thereto by means of the screws 10. The back frame has forwardly projecting lugs 11 supporting the rear end of the hood-like top 12, this top having a downwardly projecting rib 13 resting on the lugs as shown in Fig. 5. The top has downturned flanges 14 at its ends embracing the upper edges of the end members. At its forward edge the top is provided with inwardly projecting ears 15 engaged by the screws 15.

70 The rear wall has an opening 16 therein to receive the flue collar 17. A rear panel 18 extends between the rearwardly projecting ends of the base portions and is secured by means of the screws 19 engaging the ears 20 on the end members and by means of the 75 ears 21 on the panels. The front panel 22 is provided with ears 23 by means of which it is secured between the forwardly projecting ends of the base portions of the end members.

75 A supporting plate 25 is supported by lugs 26 on the end members and is further secured by screws 27 engaging the downwardly projecting flange 28 at the rear edge of the plate. This supporting plate has a downwardly projecting flange 29 at its front edge and has holes 30 therein alined with the tips 31 of the burner 32, the burner being suspended from this supporting plate.

80 The fireback 33 is mounted on this supporting plate as are also the radiating elements 34 which are of the tubular foraminated form and are arranged over the openings 30. A retaining bar 35 engages the top of the fireback and has forwardly projecting arms 36 at its ends which are secured to the end members 1. The plate 25 has a flat top on which the radiating elements are retained by means of the rod 37 which has a downwardly offset loop 38 in the central por- 85 90 95 100 105 110

tion thereof engaged by the bar-like head 39 of a screw engaging the flange 29 of the supporting plate.

The fireback is further retained by means 5 of the lugs 40 and 41 projecting inwardly from the end members to engage the front edges of the fireback. Finishing or corner plates 80 are secured by means of the screws 81 to the front flange of the supporting plate 10 to overlap the lower end of the fireback adjacent the end members.

A hearth plate 42 is mounted in front of the supporting plate, the end members being provided with supporting lugs 43 for this 15 hearth plate. The upper edge of the hearth plate rests against the retaining blocks 80, see Fig. 2. This hearth plate is spaced from the front panel 22 providing an opening between the forwardly projecting arms of the 20 end member base portions to receive the drip pan 44. This drip pan rests upon inwardly projecting ledges 45 on the end members. The hood-like top projects well forward so that it overhangs a considerable portion of 25 the drip pan when it is arranged on its support.

On each end member is a support 46 for slidably supporting the bars 47 and 48. These bars have racks 49 engaged by pinions 30 50 on the adjusting rod 51. The rod 51 has a hand-wheel 52 at each end so that the supporting bars are simultaneously adjusted. The rod 51 is supported on the rearwardly projecting brackets 53.

35 The supporting bar 48 is provided with a driving chuck 54 adapted to receive a spit 44 or other implement, and a driving chuck 56 adapted to receive the spindle 57 of a grill 58 or the like. The supporting bar 47 is 40 provided with notch-like bearings 59 and 60 for the spindles of the spit and grill.

In order to limit the rearward movement 45 of the supports when a grill is in position and thus avoid liability of injury to the parts by moving the grill so far rearward that it would engage with the frame or with other parts of the stove, I provide a stop 61 which is pivoted at 62 to be engaged by the spindle of the grill whereby it is thrown to 50 erected or operative position as shown in Fig. 6. A hook-like stop 63 on the stop 61 limits the upward swing of the stop 61 which, when in erected position, is adapted to coact with the supporting slide 46.

55 The chucks 54 and 56 are connected by gears 64 and 65. The chuck 54 is provided with a beveled gear 66 meshing with a gear 67 on the shaft 68 disposed parallel to the supporting bar 48. A housing 69 is provided 60 for the gears 66 and 67 and also for the gears 64 and 65. The shaft 68 has a non-circular portion 70 slidable through a worm gear 71 on the gear box 72. This gear 71 meshes with a gear 73 on the shaft 74 which in turn has a 65 worm gear 75 at its lower end meshing with

the worm 76 on the driving shaft 77 of the motor indicated at 78. This provides a reduction speed drive for the spit chuck 54, the grill chuck having a further reduced drive by means of the gears 64 and 65.

70 This driving connection permits the adjustment of the supporting bars to properly position the object being cooked, such as a roast indicated at 79 on the spit 55.

The shaft 70 is formed of telescoping sections connected by a shear pin 82, see Figs. 9 and 10, which is designed to break or shear off in the event that the load on the implement is too great or in the event that it comes into contact with some object to prevent turning, 80 preventing breakage at some other point in the driving mechanism.

85 In practice the supports may be adjusted to bring the roast, for instance, into close relation to the radiating elements for searing the surface and then adjusted for slow cooking if desired. The continuous turning secures uniform cooking and prevents burning.

90 I have illustrated and described my improvements in one form in which I have embodied the same in practice. I have not attempted to illustrate or describe various embodiments or adaptations which I contemplate as I believe this disclosure will enable those skilled in the art to embody or adapt my 95 improvements as may be desired.

Having thus described my invention what I claim as new and desire to secure by Letters Patent is:

1. In a structure of the class described, the 100 combination of a supporting frame, a burner mounted within said frame, radiating elements supported in operative relation to said burner, a pair of implement supports provided with racks slidably mounted on said 105 frame, an adjusting rod disposed horizontally at the rear of said frame, said frame being provided with rearwardly projecting supporting brackets for said rod, pinions on said rod coacting with said racks on said supports, 110 implement driving chucks mounted on one of said implement supports, the other implement support having implement spindle bearings, a motor mounted on said frame, speed reducing driving connections for said motor 115 to one of said implement chucks including a driven shaft permitting the adjustment of said implement supports, said driving connections including a shear pin, and driving connections from such driven chuck to the 120 other chuck.

2. In a structure of the class described, the 125 combination of a supporting frame, a burner mounted within said frame, radiating elements supported in operative relation to said burner, a pair of implement supports provided with racks slidably mounted on said frame, an adjusting rod disposed horizontally at the rear of said frame, said frame being 130 provided with rearwardly projecting sup-

- porting brackets for said rod, pinions on said rod coaxing with said racks on said supports, implement driving chucks mounted on one of said implement supports, the other 20
3 implement support having implement spindle bearings, driving means for one of said chucks permitting the adjustment of said supports, and driving connections from such driven chuck to the other chuck.
- 10 3. In a structure of the class described, the combination of a supporting frame, a burner mounted within said frame, radiating elements supported in operative relation to said burner, a pair of implement supports provided with racks slidably mounted on said frame, and adjusting rod disposed horizontally at the rear of said frame, said frame being 30
15 provided with rearwardly projecting supporting brackets for said rod, pinions on said rod coaxing with said racks on said supports, implement driving chucks mounted on one of said implement supports, the other implement support having upwardly facing notch-like implement bearing spindles, a stop operatively associated with the inner of said 25 bearings to be engaged by an implement spindle arranged therein and supported thereby to operative position, driving means for one of said chucks permitting the adjustment of said supports, and driving connections from such driven chuck to the other chuck.

In witness whereof I have hereunto set my hand.

HUBERT R. HUMPHREY.
